ATTORNEY

UNITED STATES PATENT OFFICE

CHARLES BOLZ, OF PLEASANT GROVE, NEW JERSEY

COLLAPSIBLE TUBE DISPENSING MEANS

Original application filed March 27, 1931, Serial No. 525,807. Divided and this application filed June 3, 1932. Serial No. 615,201.

My present invention has reference to a collapsible tube, of the type containing tooth paste, etc., and the invention pertains particularly to a construction of and means 5 for closing the rear end of the tube to effectively seal the same and to also provide the said rear end with a central ear or like extension that is designed to be gripped by a winding key so that the desired quantity of paste 10 may be forced through the mouth of the tube in accordance with the degree in which the key is turned on the tube.

The invention further consists of the matter divided out of my allowed application 15 upon collapsible tube dispensing means, filed by me on March 27, 1931, Serial No. 525,807 and allowed April 20, 1932.

In the drawing:

Figure 1 is a side elevation of a collapsible 20 tube in accordance with this invention.

Figure 2 is a side elevation thereof looking toward the rear end of the tube.

Figures 3, 4 and 5 are perspective views of 25 different forms of winding keys.

In the drawing the collapsible tube 1 is of the ordinary type, the same having its reduced and exterior threaded mouth portion normally closed by a removable cap 2. The tube 1, however, differs from the usual type 30 of tubes by forming the flattened sides at the rear end of the tube with central and substantially U-shaped extensions 3. The ears or extensions 3 are, of course, arranged inlapping relation and the flattened bottom has its edges

closed by a centrally bent and, therefore, cross sectionally U-shaped sealing plate or strip 4. The strip 4, in the present instance, is centrally rounded outwardly upon itself, as at 5, and the inner grooved or channeled 40 wall of the said portion 5 receives therein the ears 3. The strip 4, as well as its part 5, is tightly compressed against the bottom of the tube and its extended ears 3. The compressed strip 4 is further secured to the rear end of the tube by a continuous line of indentures 4'. The rear end of the tube is thus securely sealed.

The ears 3 and the bowed portion 5 of the closing or sealing strip 4 provide extensions 45 that are designed to be engaged by the arms

of keys. One of such keys is disclosed by Figure 3 of the drawings, and comprises a head portion 6 from which extend parallel spaced arms 7. The head 6 is in the nature of a disc, and the slot that affords the space between the arms 7 enters the head. The arms are thus rendered yieldable either inwardly or outwardly with respect to each other, so that the central projecting ear can be readily arranged between the arms and 55 the turning of the key will wind, first the ears and thereafter the body of the tube so that when the cap 2 is removed paste in desired quantities will be caused to flow or find an outlet through the tube. The key is 60 turned until the entire tube is wound upon itself so that all of the paste will be delivered from the tube. Of course, the tube is flattened or collapsed only as desired quantities 65 of paste are delivered therefrom. It is to be noted that the key engages with the tube to the rear of the bottom proper thereof and not forward of the closing or sealing strip 4 which further insures the forcible removal of 70 the entire contents of the tube.

Another form of key is illustrated by Figure 4. This key also includes a disc or similar head 8 having a substantially rectangular extension which is slotted longitudinally from its outer end to provide parallel arms 80 9. The slot between the arms does not enter the head 8, but in other respects the key is similar to that previously described.

In Figure 5 the shank 10 of the key 11 is 85 provided with a central elongated slot 12 to receive the ear extension of the tube 1 therethrough. In this instance the shank 10 is in the nature of a rigid element and is not yieldable as are the arms provided on the shanks of the keys previously described, but 90 all of the keys are, of course, employed for winding the tube upon itself to cause the contents thereof to be directed therefrom in desired quantities and at determined intervals and to likewise cause the entire collapsing of 95 the tube and the removal of the entire contents therefrom.

Having described the invention, I claim:

A collapsible tube having its open end folded upon itself to close the same, and the 100

5 said folded and flattened portion having a central ear extension, a cross sectionally U-shaped compressible sealing strip arranged over the said folded end and the said ear extension, said sealing strip having indentures entering said tube and said ear extension, and the central portion of the sealing strip and said ear designed to be engaged by a winding key.

10 In testimony whereof I affix my signature.
CHARLES BOLZ.
